CIGARETTE ROLLING MACHINE

Willem A. de Bruyne, Kitimat, British Columbia, Canada

Application November 5, 1956, Serial No. 620,274

5 Claims. (Cl. 131—37)

This invention relates to cigarette rolling machines and in particular to a cigarette rolling machine of a type and size which is adapted for hand operation and for domestic use.

Hand operated cigarette rolling machines of various types have been in common use for a number of years. In the main, they are machines which are adapted to perform only the rolling operation and do not provide any means for forming a charge of tobacco and supplying it to the rolling mechanism nor do they provide any means for supplying a paper to the rolling mechanism. As a rule both of these operations must be done by hand, the tobacco being first positioned in a pocket formed by a slack web between a pair of parallel rollers and a moistened paper then being placed on the web in such a position as to be wrapped around the charge of tobacco during the rolling operation which is performed by the machine. The present invention proposes to provide a machine in which a supply of tobacco and a supply of papers may be stored, the machine being provided with means to gather a charge of tobacco, supply it to the rolling mechanism, roll the charge of tobacco and finally wrap it with a moistened paper and then deliver the finished cigarette to a position from which it may readily be removed from the machine.

The advantages of the present invention will be readily apparent from a consideration of the following description when read in the light of the appended drawings in which like reference numerals denote like parts in the various views and in which:

Figure 1 is a perspective view of the cigarette rolling machine made in accordance with this invention, part of the machine being cut away to show the internal construction;

Figure 2 is a detailed perspective view of the mechanism inside the machine;

Figure 3 is a side elevation in cross-section of the machine shown in Figure 1;

Figure 4 is an enlarged view of a portion of the machine shown in Figure 3 with the operating mechanism in the mid-way position, and

Figure 5 is a perspective view of a cigarette paper.

Referring firstly to Figure 1 the cigarette rolling machine will be seen to comprise generally a hollow substantially cylindrical body 10 which is closed by means of end plates 11 and 12. A pair of bosses 13 and 14 which are diametrically opposed on the external surface of the body 10 serve to support it on an inverted U-shaped bracket 15 by means of bolts 16 which pass through apertures in the bracket and into threaded bolt receiving apertures in the bosses 13 and 14.

A shaft 17 extends axially through the cylindrical body and projects for a short distance on each side thereof through the end plates. To these extending portions of the shaft are secured a pair of levers 18 which extend in both directions beyond the periphery of the body. At end 18a of the levers they are joined by a yoke 19 to which is secured an operating handle 20. At the opposite

2

ends 18b the levers are joined by a rolling mechanism 37 which will be described in detail below.

The body itself is made from three independent parts which are secured in their relative positions by means of the end plates 11 and 12. These individual parts will be separately described below, during the description it being assumed that they are occupying their proper relative positions by reason of being secured to the end plate 12 (see Figure 3).

10 Referring now to Figures 1 and 3 the body portion will be seen to comprise an upper cylindrical portion 21 which includes the bosses 13 and 14 by which the mechanism is supported on the mounting bracket 15. A segment of the upper cylindrical portion 21 is cut away to receive a door 22 which is slideable in the aperture by means of a tongue 23 on the door 22 which engages a groove 24 in the edges of the aperture in the upper portion 21. The door 22 is provided with a recess 25 by which it may be gripped by the operator's finger to slide it axially of the body to gain access to the interior of the upper body portion. As is seen in Figure 1 the corresponding portion of end plate 11 is also cut away along its periphery to enable the door 22 to slide axially of the body.

25 The upper body portion 21 terminates at lower edges 26 which lie in a plane parallel to and slightly below the diameter of the body which contains the diametrically opposed bosses 13 and 14 and the shaft 17. The lower portion of the body shown generally at 27 consists of two moisture containing chambers 28 which are provided with lower surfaces 29 which, when the chambers 28 are positioned on the end plate 12 in the manner shown in Figure 3 complete the cylindrical outer configuration of the body member. The chambers are hollow and contain an absorbent material 32 which is in contact with wicks 31 extending through slots in the chambers. Water may be added to the chambers 28 through openings 28a provided in their upper surfaces for this purpose. The upper edges 30 of the chambers 28, when they are positioned as shown in Figure 3, are spaced from the lower edges 26 of the upper portion 21 to provide two oppositely opening slots S which extend in a direction parallel to the axis of the cylindrical body. The two chambers 28 are separated from one another by a space 45 which is occupied by a cigarette paper dispensing mechanism 31 which will be described in greater detail below.

Between the upper portion 21 and the moisture chambers 28 is a bed plate 32 which lies substantially along a chord of the cylinder defined by the upper and lower portions of the body. The bed plate 32 is made from sheet metal and is provided with reinforcing blocks 33 which have threaded apertures 34 at each end to receive bolts 35 (see Figure 1) which secure the end plate to the bed plate 32. The ends 36 of the bed plate 32 extend into the slots S in the periphery of the cylinder defined between the upper portion 21 and the surfaces 29 of the moisture chambers 28 and approximately divide the slots S between edges 30 of the lower portion and 26 of the upper portion into upper slots S' and lower slots S''.

60 From the above description it will be seen that when the end plates 11 and 12 are secured to the upper portion 21, to the bed plate 32 and to the moisture chambers 28 by bolts such as B (see Figure 1), the three major portions of the body will be held in their fixed spaced relationship whereby the lower surface of the body is the segment of a cylinder which has as its axis the centre of shaft 17.

65 The main shaft 17 extends along the axis of the cylindrical body and passes completely through the end plates 11 and 12 as has been described above. Secured rigidly to the extending portions of the shaft are a pair

of levers 18 which, at one end, form the operating handle 20 and which, at the other end, carry the rolling mechanism indicated generally at 37.

The rolling mechanism 37 is formed by three parallel rollers which are rotatably mounted about their axes along one side of a pair of triangular plates 41 and 42. The axes of rollers 38, 39 and 40 lie in an arc the centre of which is the centre of shaft 17. The triangular plates 41 and 42 are held in their spaced parallel relationship by means of spacer cylinder 44 which lies between the vertex of the triangular plates opposed to the side along which the rollers are rotatably mounted. A shaft 43 passes through the ends 18b of the levers 18, through an aperture in the triangular plates 41 and 42 and through the hollow cylindrical spacer 44 and is secured in position by means of nuts 45 at each end of the shaft. Thus, when operating handle 20 is moved from the position shown in Figure 3 to the position shown in Figure 1 the rolling mechanism 37 will move from a position adjacent one end of the bed plate 32 to a position adjacent the opposite end of bed plate 32.

Overlying the external lower surface of the body is a slack web of fabric 46 which is rigidly secured to the lower surface of boss 14 by means of a plate 47 which clamps the end of the fabric web between it and the lower surface of the boss 14. The plate 47 is secured in position by means of a plurality of screws 48. The width of the slack fabric web 46 is equal to the axial length of the body which, in turn, is equal to the length of the cigarette which is to be made by the machine. The other end of web 46 is secured beneath the lower surface of boss 13 by means of an adjustable mechanism which comprises a slotted roller 49. The end of web 46 is inserted in the slot of roller 49 and the roller rotated in its mounting members 50 until the web is of the proper length for optimum rolling characteristics. The roller is then locked in position by means of nut 51. The web 46, of course, lies between the external surface of the body and the rolling mechanism 37 and the length of the web 36 is sufficiently greater than the peripheral distance between its fastening points so that a pocket 46a (see Figure 3) may be formed with the web between an adjacent pair of rollers in the rolling mechanism.

Referring now to Figures 2 and 3 the mechanism which lies within the body of the cigarette rolling machine will be described in detail.

The body is considered to comprise an upper tobacco chamber and a lower chamber, the line of demarcation being the bed plate 32. Shaft 17 which passes through the upper tobacco chamber is provided, along that portion which lies between the end plates 11 and 12, with a rectangular cross-section as can be seen at 52 in Figure 2. The length of the section 52 is substantially equal to the distance between the interior faces of the end plates 11 and 12. An open ended box-like structure 53 surrounds the portion of shaft 17 of rectangular section and is a sliding fit thereto. The box-like section 53 has side walls 53a and one end wall 53b. The other end wall 54 is provided with spaced lugs 55 which extend in a direction parallel to the side walls 53a as can be seen in Figure 2. The lugs 55 are provided with coaxial drillings extending completely through them whereby two oppositely directed pushing shoes 56 may be pivotally secured thereto by means of shaft 57. At least one coil spring 58 is positioned within the box member 53 and bears at one end against the lower surface 52a of shaft 17 and, at the other end, against end face 54 of the box member 53. In this manner, as can be seen from Figure 3, the pressing shoes 56 are maintained in constant spring biased contact with the upper surface of bed plate 32.

Pivotally secured to the box member 53 at points 59 and 60 are two tobacco gathering plates 61 and 62. The tobacco gathering plates 61 and 62 pass through slots in rotatable rods 63 and 64 which serve as guide means therefor. Between the free ends 65 and 66 of tobacco

gathering plates 61 and 62 and the ends 36 of the bed plate 32 are a pair of short webs 67 and 68 which are of a width equal to the width of the tobacco gathering plates which, in turn, are of a width substantially equal to the distance between the internal surfaces of the end plates 11 and 12.

Referring now to the paper dispensing mechanism 31 which is positioned in the recess 69 between the moisture containing chambers 28, it will be seen (refer to Figure 10 4) that the paper dispensing mechanism 31 comprises a container in which a conventional package of cigarette papers 70 are stored in interfolded relationship in such a manner that when one paper is withdrawn between the guide lips 71 of the mechanism 31 a second paper is partially withdrawn in readiness for the next pass of the rolling mechanism. The holder 31 for the papers is provided with a stub shaft extending from each end thereof and seating in a vertical slot 72 cut in the internal surface of the end plates 11 and 12. This slot 72 is shown in dotted lines in Figure 4 and can be seen in perspective in Figure 1. A cover plate 73 extends between the upper surfaces 28a of the moisture containing chambers 28 to enclose the recess 69 from above. The web 46 encloses it from below. The slot 72 in the end plates 25 11 and 12 extends vertically in a direction sufficient that the lips 71 of the paper containing mechanism 31 may lie in contact with the upper surface of the web 46 so that when the rolling mechanism passes over it the end of the paper which is extending between the lips 71 will be pinched between the roll of tobacco indicated by reference characters TR and the web 46 to be withdrawn 30 from the paper containing mechanism.

Operation

35 Having described the construction of the machine the operation during one complete cycle will now be described in detail.

In the drawings the sequence of operation of the cigarette making machine may be observed from considering the drawings in the order of Figure 3; Figure 4 and Figure 1. Figure 3 shows the first position, Figure 4 shows an intermediate position and Figure 1 shows the final position of the mechanism during the rolling of a single cigarette.

45 In order to commence the operation it will be necessary for Figure 3 to be considered first. In Figure 3 it will be observed that the pushing shoe 56 has just pushed a charge of tobacco T into the pocket 46a formed by the slack web 46 between the adjacent pair of rollers 39 and 40. By referring to the opposite side of Figure 3 it can be seen how this has been accomplished. If the movement of tobacco gathering plate 61 is considered during the movement of operating handle 20 from its position in Figure 3 to the position in Figure 1 55 it will be seen that as the handle pivots the box member 53 secured to shaft 17 will cause the tobacco gathering plate to firstly move in a direction substantially parallel to its plane in the direction of the arrow A in Figure 3. Further movement of the handle 20 will cause 60 the tobacco gathering plate 61 to occupy a position corresponding to the position of tobacco gathering plate 62 shown in Figure 3. During this movement the end 61a of the plate will have approached the interior side wall 21a of the tobacco chamber 21 and will have gathered 65 within the web 61 a pouch of tobacco which will be effectively separated from the remainder of the tobacco 80 within the tobacco chamber. Approximately at the time that the end 61a of the tobacco gathering plate 61 will be approaching the lower edge 26 of the upper cylindrical portion 21 of the body due to the pivoting 70 movement of the handle 20, the pressing foot 56 will move into contact with the web 67 to push the tobacco contained therein through the slot S between the bed plate 32 and the lower edge 26 of the upper cylindrical member 21. At this time also the rolling mechanism 75

will be positioned over this slot S' in a position to receive the charge of tobacco contained by the web 67. Accordingly, from this description let it be assumed in Figure 3 that the pocket 46a contains a charge of tobacco and that the handle 20 is being moved in the direction indicated by the arrow to cause the rolling mechanism 37 to pass along the lower surface of the cylindrical body member towards the opposite end of its travel.

During the initial movement of the rolling mechanism the movement of the rollers, due to its movement relative to the web 46, will cause the charge of tobacco T within the pocket 46a to be rolled to form it into a smooth cylindrical body ready to receive a cigarette paper which is to be wrapped about it.

Referring now to Figure 4 it will be seen that as the rolling mechanism 37 passes under the recess 69 within which is positioned the paper dispensing mechanism 31, the lips 71 of the mechanism 31 will drop into the pocket 46a for a slight distance and a paper 70 which is protruding from between the lips will be pinched between the tobacco roll TR and the web which passes about roller 49 and will be caused to wrap itself around the charge of tobacco. The edge 70a of the paper 70 is unglued and the edge 70b, which is still within the mechanism 31, carries a thin film of glue along its surface as seen in Figure 5. Continued movement of the rolling mechanism 37 in the direction of the arrow in Figure 4 will cause the paper 70 to be completely withdrawn from the holding mechanism 31. This withdrawal of the paper will be completed before the pocket 46a has completely passed from beneath the recess 69 within which the papers are stored. As a final movement during the withdrawal of the paper 70 from the mechanism 31, the glued edge 70b of the paper 70 will be flicked against the moistened end 81 of an absorbent material 82 contained within the moisture chambers 28. The exposed end 81 of the absorbent material 82 acts as a wick to apply moisture to the glued edge 70b of the paper 70 thereby enabling the rolling mechanism during the remainder of its travel to complete the gluing and wrapping of the tobacco roll TR.

Referring now to Figure 1 it will be seen that when the rolling mechanism 37 reaches the limit of its travel in this one direction the tobacco gathering plate 62 and the presser shoe 56 will be ready to deliver a second charge of tobacco to the rolling mechanism.

It is to be noted in this connection that in Figure 1 the charge of tobacco is supplied to the pocket 46a which lies between the adjacent pair of rollers 38 and 39 whereas in Figure 3 the charge of tobacco is being supplied to the pocket 46a between the adjacent pair of rollers 39 and 40. In this manner when the charge of tobacco T is being applied to the pocket 46a between rollers 39 and 40 the tension applied to the belt or web 46 will pop the completed cigarette 83 (see Figure 3) from its pocket between rollers 38 and 39 and the completed cigarette will roll through slot S" and over the upper surface 28a of the moisture chambers 28 and will come to rest on the cover plate 73 of the recess 69 for the paper dispensing mechanism 31. The completed cigarette may then be removed from the machine manually through opening 84 in the end plates 11 and 12. The movement of the operating handle 20 in the opposite direction will complete the rolling of a cigarette in pocket 46a between rollers 38 and 39 and the second cigarette will be deposited on the upper surface 28a of the moisture chamber 28 at the opposite end of the travel from the position shown in Figure 3.

From the above description it will be apparent that the operation of this cigarette rolling machine is completely automatic as long as there is a supply of tobacco 80 in the upper tobacco chamber and an adequate supply of papers in the paper dispensing mechanism 31 and sufficient moisture in the moisture containing chambers 75

28. It will be appreciated that means have been provided to automatically supply a charge of tobacco to the rolling mechanism and to supply a paper to the rolling mechanism at the appropriate time.

5 The machine has been described in particular detail with reference to the attached drawings of a preferred embodiment. It will be appreciated, however, that the description and the illustrations are intended to be illustrative of the invention rather than limiting and it is contemplated that minor modifications in the construction and arrangement of parts may be made within the scope of the appended claims.

What I claim as my invention is:

1. A cigarette rolling machine comprising a hollow body divided internally by a bed plate into an upper tobacco chamber and a lower chamber, the lower chamber having an external surface which is a segment of a cylinder having an axis, a slack web overlying the cylindrical portion, a lever pivoted at the axis of the external surface of the lower chamber and extending in one direction beyond the said external surface to carry a roller mechanism riding on the slack web and extending in another direction beyond the body to form an operating handle, the roller mechanism comprising three spaced parallel rollers lying on the web and adapted to contain a loop of the web between two adjacent rollers to form a tobacco receiving pocket, the external surface of the lower chamber having two oppositely opening slots therein, one on either side of the lower chamber, means within the tobacco chamber associated with the pivoted lever to push a charge of tobacco through a slot into the tobacco receiving pocket when the pocket is positioned over the said slot and a paper dispensing and moistening mechanism mounted in a recess mid-way between the two slots to feed a moistened cigarette paper into the rolling mechanism to surround the tobacco contained therein.

2. A cigarette rolling machine comprising a hollow body having a side wall and two end walls, the body being divided internally by a bed plate into an upper tobacco chamber and a lower chamber, the lower chamber having an external surface which is a segment of a cylinder having an axis which extends between the end walls, a slack web overlying the cylindrical surface of the lower chamber, a main shaft rotatably mounted in the end walls, along the axis of the lower cylindrical surface of the body and extending through the end walls, two levers, one lever rigidly fixed to each end of the main shaft externally of the body and extending beyond the body in both senses of a diametric direction, a handle assembly joining the two levers at their one ends and a roller mechanism joining the opposite ends of the levers and overlying the slack web, the roller mechanism comprising three spaced parallel rollers lying on the web and adapted to contain a loop of the web between adjacent rollers to form a tobacco receiving pocket, the external surface of the lower chamber having two oppositely opening slots therein, one at each side of the external surface, means associated with the main shaft inside the tobacco chamber to push a charge of tobacco through the slot into the tobacco receiving pocket formed by a loop of the web between a pair of adjacent rollers when the pocket is positioned over the slot and a paper dispensing and moistening mechanism mounted in a recess mid-way between the two slots to feed a moistened cigarette paper into the rolling mechanism to surround the tobacco contained therein as the roller mechanism is moved from one end of the slack web to the other.

3. A cigarette rolling machine as claimed in claim 2 in which the means associated with the main shaft inside the tobacco chamber includes two tobacco gathering plates one pivotally secured on each side of the main shaft and extending through a guide means towards each slot in the external surface of the lower chamber, two webs, one associated with each tobacco gathering plate and joining that edge of its tobacco gathering plate remote

from the shaft and the adjacent edge of the bed plate and means mounted on the main shaft inside the tobacco chamber and spring biased to ride on the bed plate between the webs to push against one of the webs joining one of the tobacco gathering plates and the bed plate when the roller mechanism is positioned over one of the slots in the body to fill the tobacco receiving pocket between an adjacent pair of rollers.

4. A cigarette rolling machine as claimed in claim 2 in which the paper dispensing and moistening mechanism comprises a paper container pivotally mounted in a recess in the external surface of the lower chamber about an axis which is parallel to the axis of the main shaft and which is mounted in vertical slots for sliding movement, the edges of the recess adjacent the cylindrical wall being provided with wicks extending into chambers adapted to receive water on each side of the recess.

5. A cigarette rolling machine comprising a hollow body having a side wall and two end walls, the body being divided internally by a bed plate into an upper tobacco chamber and a lower chamber, the lower chamber having an external surface which is a segment of a cylinder having an axis which extends between the end walls, a slack web overlying the external surface of the lower chamber, a main shaft rotatably mounted in the end walls along the axis of the external surface of the lower chamber and extending through the end walls, two levers, one lever rigidly fixed to each end of the main shaft externally of the body and extending beyond the body in both senses of a diameter direction, a handle assembly joining the ends of the levers at their one ends and a roller mechanism joining the opposite ends of the levers and overlying the slack web, the roller mechanism comprising three spaced parallel rollers lying on the web and adapted to contain a loop of the web between adjacent pairs of rollers to form the external surface of the lower chamber having two slots therein, one open-

ing in one direction at one side of the external surface and the other opening in an opposite direction at the other side of the external surface, the two slots being parallel to the rollers of the roller mechanism and to each other, a tobacco gathering plate pivotally secured on each side of the main shaft and extending through guide means towards each slot in the body, two webs, one associated with each tobacco gathering plate and joining that edge of each tobacco gathering plate remote from the shaft to the adjacent edge of the bed plate and means mounted on the main shaft inside the tobacco chamber and spring biased to ride on the bed plate to push against one of the webs joining one of the tobacco gathering plates and the bed plate when the roller mechanism is positioned over one of the slots in the external surface of the lower chamber to fill the tobacco receiving pocket between adjacent pairs of rollers and a paper dispensing and moistening mechanism comprising a paper container pivotally mounted in a recess in the bottom cylindrical wall of the body about an axis which is parallel to the axis of the main shaft and which is mounted in vertical slots for sliding movement, the edges of the recess adjacent the cylindrical wall being provided with wicks extending into chambers adapted to receive water on each side of the recess, the paper dispensing mechanism delivering a moistened cigarette paper into the rolling mechanism to surround the tobacco contained therein as the roller mechanism is moved from one end of the slack web to the other.
